UNITED STATES PATENT OFFICE

2,470,827

ELECTRIC STRIKER SYSTEM FOR CHIMES

Milo F. Miller, Kansas City, Mo.

Application June 3, 1946, Serial No. 673,973

7 Claims. (Cl. 177—7)

1

This invention relates to sound producing apparatus in general and particularly to signals of the type having electrically operated striker plungers for movement toward the bars that are closely associated with hollow tubes.

The important object of this invention is to provide a striker system for chimes or the like provided with a freely reciprocable striker plunger that is mounted under the influence of magnetic lines of force created by the energization of at least two coils, one of which positions the said striker plunger with respect to the bar associated therewith, while the remaining coil motivates the plunger at a time when the first mentioned coil is not operative.

A further aim of this invention is the provision of a striker system for chimes having therein and as a part thereof a specially formed striker plunger, the character whereof is such as to cooperate with a pair of coils and associated bars to insure the creation of a sound of a fixed predetermined character.

A yet further object of my invention is the provision of a striker system for chimes having a pair of tubes in juxtaposition with a number of bars of different lengths whereby each tube has formed therein a number of chambers to cooperate with each of the bars for the purpose of minimizing the number of tubes constituting the chime assembly.

Further aims of the invention are to provide a striker system for chimes that is easily and quickly adjustable by the person installing the chimes; that is capable of being tuned by relatively shifting easily accessible parts of the chime system; and that is devoid of springs or other yieldable means having an influence upon the striker plunger.

Other aims of the invention and the manner in which the parts of the striker system operate to produce novel results through a minimum number of elements will appear during the course of the following specification referring to the accompanying drawing, wherein:

Figure 1 is a front elevational view of a striker system for chimes made in accordance with the present invention.

Fig. 2 is a transverse sectional view taken on line II—II of Fig. 1 and looking in the direction of the arrows.

Fig. 3 is a fragmentary cross sectional view taken on line III—III of Fig. 1.

Fig. 4 is an enlarged fragmentary detailed sectional view through the end portion of a striker

2

plunger forming a part of the assembly illustrated in Fig. 1.

Fig. 5 is a similar sectional view illustrating a modified form of a plunger for the striker system.

Fig. 6 is a front elevational view of a striker system for chimes illustrating the manner in which a number of bars may be used for a pair of tubes; and

Fig. 7 is a sectional view taken on line VII—VII of Fig. 6.

It has long been known that the employment of springs or other retrieving resilient elements in a striker system for chimes is objectionable and establishes an uncertain factor because the movement of the striker plunger is not constant and does not, therefore, engage the associated bars with the same amount of force each time the striker system is operated. The relatively simple expedients forming a part of the striker system shown in the accompanying drawing and which are capable of setting the striker plunger each time the chime is operated, will produce an exceptionally desirable unit.

The form of the invention illustrated in Figs. 25 1 to 3 inclusive, comprises a base 10 upon which is mounted a pair of brackets 12 slotted as at 14 to adjustably receive screws 16 that enter base 10. Brackets 12 are preferably from iron or other material that is highly pervious to magnetism. 30 There are two brackets and each carries a bar 18 disposed adjacent to a cooperating hollow tube 20 that likewise is retained in operative position by the corresponding bracket 12.

An opening 22 formed in the side wall of each tube 20 performs the usual function as is well known in the art. A fixture 24 secured to base 10 supports a brass tube 26 within which striker plunger 28 is reciprocably mounted. A coil 30 is on one end of tube 26 and a coil 32 is at the other end of said tube. One of the coils may be fixed directly to tube 26 and for purpose of illustration, coil 30 has been so shown. Coil 32 is provided with a sleeve 34 that circumscribes tube 26 and it is this sleeve 34 that directly carries coil 32.

A set screw 36 in sleeve 34 may be manipulated to adjust coil 32 with respect to coil 30. The ends of coils 30 and 32 are shielded by walls 38 preferably made of non-metallic material or other substance that is not greatly pervious to magnetic lines of force. This structure is important because it is desired that the said lines of force created by the energization of these coils 55 should be confined to the space between the

walls 38 to effectively act upon specially constructed striker plunger 28.

Striker plunger 28 lies between bars 18, as clearly illustrated in Fig. 3 and each end strikes a bar when a master switch 40 is moved to successively close points 42, 44 and 46 thereof. Point 48 on the swingable arm of switch 40 contacts these points 42, 44 and 46 in a manner hereinafter to be described. The source of current in this instance is a battery 50 and wires or suitable conductors create the circuit which includes the source of energy and switch 40 with all its component parts. It also includes the two coils 30 and 32.

Striker plunger 28 is specially designed with reference to coils 30 and 32 in that it has two sections numbered 52 and 54 respectively of magnetic material that are attracted by the magnetic lines of force established when the coils 30 and 32 are energized. The length of these sections 52 and 54 is substantially the same as the length of the said coils for the reasons more fully herein-after to be described.

The interconnecting portion of plunger 28 between sections 52 and 54 is of non-magnetic material. Likewise, the tips 56 and 58 at the ends of plunger 28 are held in position by identical collars 60 that are of non-magnetic substance. Reference to Fig. 5 will teach the manner in which tips 56 and 58 are held in place on plunger 28 to obtain the rebound necessary in the contemplated functioning of the striker system.

Tip 58 is of leather or analogous fibrous substance and a resilient disk 62 is interposed between the inner end of tip 56 or 58 and the outer end of section 52 or 54 as the case may be.

Collar 60 bridges the resilient disk 62 and extends over a portion of the length of tip 56 or 58 as well as over a portion of the adjacent section 52 or 54 respectively of plunger 28.

In the modified form of the plunger shown in Fig. 4, tip 64 is likewise of leather and disk 66 is of rubber or similar resilient material. Section 68 of magnetic substance, is confined within a tube 70 of non-magnetic material which serves the function of holding together the section 68, disk 66 and tip 64.

After screws 16 have been tightened to hold brackets 12 in the adjusted position and thereby to maintain bars 18 in such spaced condition as will suit the desire of the operator, coil 32 may be shifted along the length of tube 28 by manipulating set screw 36 as such is needed. When the system is electrically assembled, as shown in Fig. 2, a movement of switch 40 to contact point 42 will energize coil 32 through the simple wiring circuit illustrated, whereupon plunger 28 will be "set" because section 52 of plunger 28 will be centered between walls 38 of coil 32 due to localizing the magnetic lines of force. When switch 40 continues to be manipulated and point 43 reaches point 44, coil 32 will be de-energized and coil 30 will be energized to cause plunger 28 to move quickly to the right as viewed in Fig. 3. Such movement is established by virtue of the magnetic pull upon section 54 by the lines of force confined between walls 38. This quick shifting of plunger 28 will establish a sufficient amount of momentum to cause the plunger to move beyond the confines of coil 30 where tip 58 will strike bar 18 to vibrate the same. Continued movement of switch 40 to close contacts 46 and 48 will cause deenergization of coil 30 and energization of coil 32, whereupon section 52 of plunger 28 will be attracted and tip 56 will be forced against the

proximal bar 18 in the manner just set forth. Switch 40 is rotatable, and while it is being returned to its point of beginning, neither of the coils will be energized and plunger 28 will come to rest wherever the rebounding force happens to dictate.

From the immediate foregoing, it will be clear that a definite setting of plunger 28 is always established when switch 40 is being moved through its cycle. A definitely constant amount of force is always insured therefore, to cause plunger 28 to strike the bars 18 with precisely the same character of impact and, therefore, a like sound is always assured.

The form of the striker system illustrated in Figs. 6 and 7 embodies the principles as above specified but permits the construction of a chime that will produce a number of different sounds greater than the number of tubes utilized. In the form shown, a tube 100 is divided into a chamber 102 and a chamber 104 adjacent to each of which is mounted a bar 106 and 108 respectively, the vibrations whereof are transmitted to chambers 102 and 104 through openings 110 and 112 respectively. A partition 114 in tube 100 segregates chambers 102 and 104 and a shiftable partition 116 at one end of tube 100 and within chamber 102, permits varying the length of this said chamber and a movable partition 118 in chamber 104 likewise allows varying the cubical capacity thereof.

A tube 120 is divided into two effective chambers 122 and 124 respectively. Partitions 126 within tube 120 set off these chambers and openings 128 and 130 respectively permit vibrations from bars 132 and 134 to enter the chambers adjacent thereto. Thus, a chime assembly which appears to have but two tubes may create four distinct sounds in the order desired and as dictated through the wiring of a number of coils. Coils 136 and 138 are mounted upon a bracket 140 carried by base 142. The plunger 144 which is actuated by these coils 136 and 138 strikes bar 132 when coil 138 is energized and after coil 136 has been energized to "set" plunger 144 in precisely the same manner as described with respect to Fig. 3. Coils 146 and 148 carry plunger 150 and this plunger is positioned to strike bar 133 as above mentioned. In this instance, however, coil 148 is the "setting" coil and coil 146 is the "driving" coil. Coils 146 and 148 are mounted upon a bracket 152 through the medium of a set screw and slot construction 154 and 156 respectively to allow shifting of the coils toward and from each other. Such shifting of course, will be with respect to the magnetic sections 52 and 54 of the plunger and will determine the amount of force with which the plunger strikes bar 133. Coils 136 and 138 are mounted in precisely the same manner as are coils 146 and 148. Coils 158 and 160 carry plunger 162 to strike bar 135 and coils 164 and 166 carry plunger 168 to strike bar 134.

The operation of these coils and the manner of setting their associated plunger is the same as above set down. Thus, it will be clear that a chime assembly having but a pair of tubes may be caused to create at least four distinct tones and these tones may be tuned to suit the whims or conditions confronting the operator. No springs or other resilient means for holding the various plungers are used and a positively electrical setting is assured prior to forcing the plunger against its related bar.

It will be clear from the foregoing that striker systems for chimes and chime assemblies of wide-

ly varying characteristics may be made to embody this invention, all without departing from the spirit thereof and scope of the appended claims.

Having thus described my invention, what I claim as new and desire to secure by Letters Patent is:

1. In a striker system for chimes comprising a base; a resonant tube and chime bar assembly carried by the base; a pair of coils on the base to one side of the chime bar; and a striker plunger extending into and under the influence of the coils, one of the coils serving, upon energization thereof, to set the plunger in a predetermined position prior to its movement against the chime bar.

2. In a striker system for chimes comprising a base; a resonant tube and chime bar assembly carried by the base; a pair of coils on the base to one side of the chime bar; and a striker plunger extending into and under the influence of the coils, said striker plunger having a pair of spaced apart sections of magnetizable material, the lengths of said sections being substantially the same as the lengths of the respective associated coils, the distance between the said sections being less than the distance between the coils whereby when one section is in alignment with a coil the remaining section is offset with respect to the other coil.

3. In a striker system for chimes, a plunger comprising a metallic body; a tip of non-dampening substance on the end of the body; a pad of resilient material interposed between the end of the body and said tip; and a tubular element rigid to the body and extending longitudinally therefrom to circumscribe the said pad and a portion of the tip.

4. In a striker system for chimes comprising a base; a pair of resonant tube and chime bar assemblies carried by the base in spaced apart relation, with the chime bars of the assemblies substantially parallel; a reciprocable striker plunger disposed between the bars with its axis substantially perpendicular to said bars; a pair of coils circumscribing the plunger for reciprocating the latter upon alternate energization thereof; an electric circuit for said coils; and a switch for successively closing the circuit to set the plunger at a predetermined position upon energization of one coil, moving the plunger against one chime bar upon energization of the other coil, and moving the plunger against the other chime bar as the one coil is again energized.

5. In a striker system for chimes comprising a base; a pair of resonant tube and chime bar assemblies carried by the base in spaced apart relation, with the chime bars of the assemblies

substantially parallel; a reciprocable striker plunger disposed between the chime bars with its axis substantially perpendicular to said chime bars; a pair of coils circumscribing the plunger for reciprocating the latter upon alternate energization thereof, said plunger being freely slidable within the coils; an electric circuit for said coils; and a switch for successively closing the circuit to set the plunger at a predetermined position upon energization of one coil, moving the plunger against one chime bar upon energization of the other coil, and moving the plunger against the other chime bar as the one coil is again energized.

6. In a striker system for chimes comprising a base; a pair of resonant tube and chime bar assemblies carried by the base in spaced apart relation, with the chime bars of the assemblies substantially parallel; a reciprocable striker plunger disposed between the chime bars with its axis substantially perpendicular to said chime bars; and a pair of coils circumscribing the plunger for reciprocating the latter upon alternate energization thereof, one of said coils being joined to a source of current to set the plunger in a predetermined position prior to its movement toward one of the chime bars to strike the same, the other coil being joined to said source of current to move the plunger from said position against said one chime bar.

7. In a striker system for chimes comprising a base; a pair of resonant tube and chime bar assemblies carried by the base in spaced apart relation, with the chime bars of the assemblies substantially parallel; a reciprocable striker plunger disposed between the chime bars; a pair of coils circumscribing the plunger for reciprocating the latter upon alternate energization thereof, the other coil being joined to said source of current to move the plunger from said source of current against said one chime bar; and means for energizing said one coil to move the plunger from said one chime against the other chime bar.
